(No Model.)

W. B. GUILD.

FIRE EXTINGUISHING APPARATUS AND CARTRIDGE THEREFOR.

No. 552,123.

Patented Dec. 31, 1895.

UNITED STATES PATENT OFFICE.

WALTER B. GUILD, OF NORWOOD, MASSACHUSETTS.

FIRE-EXTINGUISHING APPARATUS AND CARTRIDGE THEREFOR.

SPECIFICATION forming part of Letters Patent No. 552,123, dated December 31, 1895.

Application filed February 18, 1895. Serial No. 538,858. (No model.)

To all whom it may concern:

Be it known that I, WALTER B. GUILD, of Norwood, in the county of Norfolk and State of Massachusetts, have invented certain new and useful Improvements in Fire-Extinguishing Apparatus and Cartridges Therefor, of which the following is a specification.

It is the purpose of this invention to provide a hose connection with a stand-pipe or other water-supply of a fire-extinguishing apparatus with means whereby it can be readily charged and recharged with a chemical cartridge so constructed and arranged that the ingredients of the cartridge may co-act with the water passing through the hose when the latter is in use to effect the extinguishment of a fire.

To these ends the invention consists of a cartridge for use in chemical fire-extinguishing apparatus of novel construction adapted to be separately made and sold as an article of manufacture and to be used so as to readily recharge a fire-extinguishing apparatus with chemicals for the purpose aforesaid.

The invention also consists of an apparatus connected with a stand-pipe or other suitable water-supply or hose connection, which apparatus is adapted to have my improved cartridge employed in connection therewith.

The invention will first be described in detail, and then pointed out with particularity in the appended claims.

Reference is to be had to the annexed drawings, and to the letters marked thereon, forming a part of this specification, the same letters designating the same parts or features, as the case may be, wherever they occur.

Of the drawings, Figure 1 is a side elevation, partially in section, of a hose connection with a stand-pipe equipped with my invention. Fig. 2 is a similar view of a slightly different embodiment of the invention. Fig. 3 is a sectional view taken on the line 3 3 of Fig. 1. Fig. 4 is a perspective view of one form of my improved chemical cartridge. Fig. 5 represents a sectional view of another form of cartridge. Fig. 6 is a cross-sectional view of still another modification.

In the drawings, Figs. 1 and 2, *a* designates a stand-pipe connected with a source of water-supply.

b is a branch provided with a valve *c* and

with a coupling *b'* adapted to secure a pipe *d* to said branch. The pipe *d* is provided with a cartridge-receiver *e*, which is a chamber, 55 preferably of cylindrical form, communicating with the pipe *d*, which serves as an inlet of the receiver. The receiver is also provided with an outlet, which, as shown in Figs. 1 and 3, is a nipple *m* secured to one side of the receiver and adapted to act as one member of a coupling by which the hose *o* may be secured to the receiver, while in Fig. 2 said outlet is shown as a nipple *m'* formed on one end of the receiver *e* and also adapted to serve as 65 a member of a coupling.

f is the cartridge, made to substantially fit the interior of the receiver and containing chemical ingredients, such as acid and soda in dry or granular form, whose reaction when 70 brought into contact in the presence of water releases a gas and increases the efficiency of the water for fire-extinguishing purposes. The cartridge is constructed to hold the chemicals separated from each other so long as water is excluded therefrom, and to permit free access to the chemicals of water admitted to the receiver *e*, the construction of the cartridge being such that the water can pass freely through it from the inlet to the outlet 75 of the reservoir. The cartridge is or may be composed of a cylindrical foraminous external shell, which may be composed of cloth the meshes of which are sufficiently open to permit the passage of water through them 80 without permitting the escape of the undissolved chemicals, and suitable heads or end pieces, which may be of the same or any suitable foraminous material, such as wire-cloth. The external shell shown in Figs. 1, 3, and 4 85 may be supposed to be of foraminous material, such as cloth, although I have not attempted to represent such material in the said figures. The cartridge is shown in Figs. 1, 3, and 4 as provided with a longitudinal central 90 tube *f'* of wire-cloth forming a passage through the cartridge from end to end, the walls of said tube supporting the chemicals which are placed in the annular space between the tube and the body or shell of the 95 cartridge.

I prefer to employ a foraminous external shell when the outlet is arranged in one side of the reservoir, as shown in Figs. 1 and 3,

since the water is thus enabled to pass freely through the shell of the cartridge and through the outlet in the side of the reservoir. I do not limit myself to this construction of the 5 cartridge, however, and may dispense with the central tube. I may also make the shell of the cartridge of paper, cardboard, or other material not essentially foraminous, providing it with heads of foraminous construction, 10 so that the water can pass freely through the cartridge from end to end, said heads confining the chemicals in the cartridge.

The construction last described is particularly suited to the receiver shown in Fig. 2, 15 in which the inlet is at one end and the outlet at the opposite end, the water passing into one end of the cartridge and out at the other.

f^2 f^2 represent partitions subdividing the interior of the cartridge into two compartments, one containing the acid and the other the soda. Said partitions are constructed to prevent direct contact between the two chemicals, and thus prevent one chemical from neutralizing the other. The partitions are so 25 constructed, however, that they will not prevent the free passage of the water through the chemicals, so that while the chemicals are separately dissolved the solutions will be mixed as the water passes or after the water 30 has passed through the cartridge. Said partitions may be of paper or any other suitable material.

One end of the receiver may be provided with a removable head j , so that the receiver 35 may be readily resupplied with a cartridge when necessary and obstructions in the receiver removed.

A strainer s may be arranged in the outlet-port m of the receiver to prevent the discharge 40 of the undissolved chemicals with the water.

In Fig. 1 I have shown the cartridge-receiver as forming the barrel of a hose-reel, the axis of which is formed by the pipe d , while in Fig. 2 the hose is placed on a holder 45 n connected with the stand-pipe.

With this invention the cartridge-receiver containing a cartridge may be attached in a suitable manner to a supply-pipe and a hose, also connected therewith, so that when the 50 water is turned on from the supply-pipe it may rush through the cartridge and gradually dissolve the chemicals, which will combine with the water and enhance the fire-extinguishing properties of the latter.

By the use of a cartridge as described the device is made capable of being charged and renewed by persons of the most ordinary skill, so that the invention may be used in shops 55 and dwellings and kept in usable condition 60 by domestics or ordinary laborers.

The prime object of this invention is to provide a chemical fire-extinguisher which may be employed in connection with hose connected with a stand-pipe or the like without 65 interfering with the flow of the water to any appreciable extent, but enhancing the fire-extinguishing properties of the latter. It is evi-

dent that should a small amount of chemical be desired for the purpose of using in incipient fires two valves could be used, the larger 70 one not to open into the receiver, but to carry a large stream of water only, while a smaller valve for a small hose could open into the receiver. In such construction the chemical could be used more sparingly, while the large 75 stream could be used to deluge the fire, and neither interfering with the other, although both could be attached to the same branch or hose-rack. The small hose to be used alone would save great damage from water, while 80 the chemical would give greater efficiency than many times the amount of water alone.

My invention is not limited to a cartridge as separate and distinct from a receiver, for the cartridge may consist of a metal shell 85 coupled to the supply-pipe and formed with partitions for separating the chemicals and a foraminous tube communicating with the compartments formed by the partitions. Such a construction is illustrated in Fig. 6, 90 wherein the letter z designates a cylindrical metallic shell designed to be coupled to the water-pipe branch after the manner of coupling the shell e in Fig. 2, and to be similarly equipped with means for coupling the hose to 95 it. This shell is formed with radial webs or partitions z' , and in the center of the shell there is placed a foraminous tube z^2 , fitting close up to the inner edges of the said partitions z' , and thus bounding the compartments 100 at their inner sides. The shell is charged with one kind of chemical in one compartment formed by the partitions, and with another kind of chemical in the other compartment, and these chemicals are kept separate by the 105 partitions and by the foraminous tube, so that only under the influence of water passing through the cartridge will they be allowed to unite. If found necessary a soluble film, z^3 may be wrapped around the foraminous 110 tube to prevent fumes of the chemicals from meeting.

The central tube will be in communication with the water-passage, so that when the water is turned on it may reach the chemicals 115 through the walls of the tube.

Having thus described my invention, what I claim is—

1. A cartridge for fire-extinguishing apparatus, comprising a shell constructed to hold 120 granular chemicals and provided with internal partitions which subdivide the interior of the shell into compartments and prevent the reaction of the chemicals upon each other, said compartments having foraminous portions 125 which permit the free passage through the compartments of water admitted to the shell.

2. A cartridge for fire-extinguishing apparatus embodying in its construction a foraminous tube extended through the ingredients 130 and a covering enveloping the entire cartridge excepting the ends of the tube.

3. In a fire-extinguishing apparatus, the combination of the following parts, namely,

first, a fixed supply-pipe; secondly, a cartridge receiver having an inlet port communicating with the supply-pipe, an outlet port provided with a coupling member and a removable end or head; and thirdly, a chemical-containing cartridge having a central foraminous tube or passage communicating with the inlet port, as set forth.

4. In a fire-extinguishing apparatus, the combination of the following parts, namely, first, a fixed supply-pipe; secondly, a cartridge receiver having an inlet port communicating with the supply-pipe, an outlet port located in one side of the tube provided with a coupling member and a removable end or head; and thirdly, a chemical-containing cartridge having a central foraminous tube or passage communicating with the inlet port, and a foraminous covering through which the chemically

charged water passes to the outlet port, as set forth.

5. A cartridge for fire-extinguishing purposes, the same comprising a shell having partitions dividing its interior into compartments for containing different kinds of chemicals; and a foraminous tube in the shell and bounding the compartments at their inner sides,— the said cartridge adapted to be incorporated into a water system with the foraminous tube in communication with the water-passage. 30

In testimony whereof I have signed my name to this specification, in the presence of two subscribing witnesses, this 29th day of December, A. D. 1894.

WALTER B. GUILD.
